GASTON SAUTTER, OF PARIS, FRANCE.

HOT-LIQUID POWER PLANT.

No. 884,888.

Specification of Letters Patent. Patented June 15, 1909.

Application filed April 8, 1905. Serial No. 253,713.

To all whom it may concern:

Be it known that I, GASTON SAUTTER, of Paris, France, have invented a new and useful Improvement in Hot-Liquid Power Plants, which improvement is fully set forth in the following specification.

This invention has for its object the recovery of energy from hot liquids by the action of a vacuum on these liquids, combined with the employment of a steam turbine.

In industries in which hot liquids are employed, such as the chemical and dyeing industries, works in which organic matters are extracted, etc., it often happens that large quantities of hot water at a temperature of about 100° C. or even above must be discharged.

The quantity of energy represented by the volumes of water thus thrown away is often considerable; not only is this heat completely lost, but the discharge of the liquid sometimes causes considerable nuisance.

This invention has for its object to recover a portion of the energy thus lost, by employing the heat of the liquid itself for vaporizing a fraction of its weight. The steam thus produced is then utilized in a turbine and the work of the turbine is employed for any desired purpose.

In order to vaporize a portion of the liquid, it is necessary to submit it to the action of a vacuum and for this purpose it is put into communication with a condenser. A fall in pressure is thus produced between the initial pressure of the hot liquid (a pressure which may be lower than, equal to or greater than atmospheric pressure) and the depression due to the condenser. A fall in temperature corresponds to this fall in pressure which is utilized to vaporize a fraction calculable beforehand by the thermo-dynamic laws of the weight of the liquid. Steam is thus generated, the weight of which depends upon the weight of the hot liquid to be got rid of. This steam is generated at a pressure lower than atmospheric pressure; it has therefore a large specific volume.

The whole process is carried out in such a manner that the diminution of pressure caused by the condenser is divided into two stages: the first fall in pressure takes place at the surface of the hot liquid itself, the second fall in pressure takes place between the vessel in which the hot liquid is vaporized and the condenser itself. It is this second

fall in pressure which allows the steam generated to flow through and drive the turbine.

If P is the absolute pressure at which the vaporization takes place and p the absolute pressure of the condenser, the turbine utilizes the fall in pressure $P-p$; P being supposed to be lower than atmospheric pressure.

Figure 1 is a view in elevation of one form of the invention. Fig. 2 is a similar view of a slightly modified form of the invention.

The arrangement illustrated in Fig. 1, of the annexed drawing, consists of a vacuum chamber or condenser 1, a fluid motor in the form of a steam turbine 2, and a closed vessel or receptacle 3, into which the hot liquid flows and in which there is the partial vacuum due to the condenser.

4 is the pipe supplying the hot liquid to the vessel 3; 5 is a bent pipe through which the steam generated passes out from the vessel 3 into the turbine 2.

6 is the exhaust pipe from the turbine 2 leading to the condenser 1. The non vaporized liquid flows out from the vessel 3 through the outlet pipe 7, the end 8 of which is bent into a goose neck, 9 being the outlet orifice.

Assuming that H is the atmospheric pressure measured by the height of a column of the liquid, h the height of liquid, which added to the absolute pressure in the vessel 3, balances the atmospheric pressure, P the absolute pressure (in terms of the height of a column of liquid) in the vessel 3, and p the pressure in the condenser, also measured by the height of a column of liquid. It will be seen that there is an equation: $P = H - h$.

The total diminution of pressure created by the condenser 1 is equal to $H-p$. It is divided into two parts: The diminution $(H-P)$ which represents the fall of pressure in the hot liquid from its initial condition to the pressure in the vessel 3 and a second portion $(P-p)$ which represents the fall of pressure in the steam generated in the vessel 3, the steam expanding through the steam turbine 2 into the vacuum in the condenser 1.

Of course the principle is equally applicable if the hot liquid is originally at a pressure above atmospheric pressure; in which case the initial fall in pressure no longer commences with atmospheric pressure H , but with a higher pressure. On the other hand, the arrangement may also be applied to a liquid at a pressure lower than atmospheric

pressure and at a temperature lower than 100° C.

The method by which energy is recovered by means of a condenser and a turbine is 5 the same in all cases.

The following example will better explain the present invention. Let 100° C. be the temperature of the hot liquid which is assumed to be at atmospheric pressure. Let 10 also O K 15 be the absolute pressure inside the condenser. If the suitable proportion of the steam turbine be suitably calculated, the absolute pressure in the vessel 3 may be caused to be: say O K 60; the fall in temperature in the hot liquid is then 15°. It will be seen that each kilogram of liquid frees 15 calories which are utilized to vaporize a fraction of the weight of the liquid. The steam thus produced in the vessel 3 is at 20 an absolute pressure of O K 60; it therefore expands in the turbine 2 from the absolute pressure of O K 60 to the absolute pressure in the condenser which is O K 15. This method of employing energy in the form of 25 low pressure steam would be altogether impracticable if a piston motor were employed. The dimensions of piston motors being proportional to the volume of steam which they receive, very large sizes would be required, 30 for in the preceding example the specific volume of the kilogram of steam at the pressure of O K 60 is 2760 liters. If it be desired to obtain a power of several hundred horse, motors of such enormous size would be 35 required as to be absolutely impossible in practice. The steam turbine on the contrary, in which the fluid acts by speed, is still of a quite practicable size with large volumes of steam, it therefore lends itself particularly 40 to the employment of low pressure steams. Moreover the efficiency of turbines particularly with low pressure steams is excellent for the main causes of loss, that is to say, friction of the steam on the wheels, is reduced to a 45 minimum. The arrangement shown in Fig. 1 allows hot liquids submitted to the action of a vacuum to be ejected without employing such pumps. In fact the vessel 3 is connected with the atmosphere through the pipe 50 7—8, which is bent into a goose neck. This has the result that in proportion as the hot liquid passes into the vessel, it flows out with regularity through the orifice 9 of the pipe 8.

The apparatus should be designed in such 55 a manner that the difference in level between the orifice 9 and the surface of the liquid in the vessel 3 is equal to the value $H - P$, which represents in terms of the height of a column of liquid the difference between atmospheric 60 pressure and the pressure in the vessel 3. On the other hand, the goose neck 8 must be approximately equal to the height $\frac{1}{2}$; this condition is necessary for starting the apparatus in order that the goose neck 8 should 65 always be full of liquid at the time of start-

ing. In fact the action of the condenser when it commences to make itself felt, will cause the liquid to rise in the tube 7 by emptying the goose neck 8; it is therefore necessary that the height of the liquid in the pipe 7 should be at least equal to the height h , otherwise air would enter through the pipe 8 into the vessel 3. Another condition is necessary for the working. The hot liquid must be prevented from being sucked into the turbine 2. For this purpose the pipe 5, which leads steam into the turbine, must be bent and there must be a difference in level equal to the barometric pressure H measured in terms of the height of a column of liquid between the orifice 9 of the goose neck and the upper level of the pipe 5. The apparatus thus constructed works normally under all conditions; it is only necessary to put the condenser into operation to gradually produce the vacuum in the vessel 3 and to generate steam which passes into the turbine 2. When the volume of hot liquid varies the level in the vessel 3 will also vary slightly and the delivery through the orifice 9 will be proportionally altered. Fig. 2 relates to the same arrangement in which the vessel 3 and its outlet pipe are arranged below the ground level. The liquid in this case flows into a pit 10, the liquid is then raised by a pump 12 through a pipe 11, provided with a valve. The respective heights of the pipes 7 and 8 should follow the same law as in the previous case. The pump 12 is necessary in this case because the liquid must be raised from a low level to the level of the water drain.

Having now particularly described and ascertained the nature of my said invention and in what manner the same is to be performed, I declare that what I claim is:

1. An apparatus for obtaining mechanical energy from hot water, comprising a closed receptacle for said hot water, means for removing surplus hot water from the receptacle, whereby a reduction of pressure is obtained in said receptacle and steam is produced, a vacuum condenser, a fluid motor, a connection between said receptacle and said motor, whereby the steam is conducted to the motor, and a connection between the exhaust outlet of the motor and the condenser.

2. An apparatus for obtaining mechanical energy from waste hot water, comprising a closed receptacle for said waste hot water, a discharge pipe having one end connected to the receptacle below the water line of the same and having its other end below said level and open to the atmosphere, a steam pipe connected to the receptacle above the water level therein, a steam motor arranged to receive steam from said steam pipe, and a vacuum condenser connected with the exhaust side of the said motor.

3. An apparatus for obtaining mechanical energy from the hot water waste from indus-

- trial plants comprising a closed receptacle for said waste, a pipe supplying the waste to the receptacle above the level of the liquid therein, means for constantly removing surplus water 5 from the receptacle, a vacuum-producing condenser, a connection between said condenser and the receptacle above the level of the liquid therein, and a rotary motor interposed between the condenser and the receptacle and forming a part of the said connection.
- * 4. An apparatus of the character described comprising a hot-liquid-receiving vessel, a goose-necked discharge pipe connected with one portion thereof, a steam supply pipe connected with another portion thereof, a turbine engine with which the latter pipe connects, and a condenser in communication with the engine.
- 20 5. An apparatus of the character described comprising a hot-liquid-receiving vessel, a goose-necked discharge pipe connected with one portion thereof, an approximately goose-necked steam supply pipe connected with another portion thereof, a turbine engine with which the latter pipe connects, and a condenser in communication with the engine.
6. An apparatus of the character described comprising a hot-liquid-receiving vessel, a discharge pipe connecting therewith below the level of the liquid, a bent steam supply pipe connecting with the vessel above the level of the liquid therein, a turbine engine with which the latter pipe connects, and a condenser in communication with the engine.
- 30 7. An apparatus of the character described comprising a hot-liquid-receiving vessel, a goose-necked discharge pipe connecting therewith below the level of the liquid, a bent steam supply pipe connecting with the vessel above the level of the liquid therein, a turbine engine with which the latter pipe connects, and a condenser in communication with the engine.
- 40 8. An apparatus of the class described, comprising a hot-liquid-receiving vessel, a goose neck discharge pipe leading from the lower portion thereof, a steam pipe leading from the upper portion thereof above the level of the liquid therein, a turbine engine arranged to receive the steam from the latter pipe, and a condenser in communication with the engine the discharge orifice of the goose neck being substantially two-thirds the distance downward from the level of the liquid 55 in the vessel to the lowermost point of the goose neck.
9. An apparatus of the class described comprising a hot-liquid-receiving vessel, a turbine, vacuum means communicating with the turbine, a discharge pipe leading from the vessel, and a steam pipe connecting the vessel to the turbine, the difference in level between the outlet of the discharge pipe and the point of junction between the steam pipe 60 and turbine being at least equal to the height of a barometric column of the liquid.
10. An apparatus of the class described, comprising a hot-liquid-receiving vessel, a turbine, vacuum means communicating with the turbine, a goose neck discharge pipe leading from the vessel, and a bent steam pipe connecting the vessel to the turbine, the difference in level between the outlet of the goose neck 70 and the bend of the steam pipe 75 being substantially equal to the height of a barometric column of the liquid.
11. An apparatus of the class described comprising a hot-liquid-receiving vessel, a turbine engine, a condenser communicating with the engine, a goose neck discharge pipe leading from the lower portion of the vessel, and a bent steam pipe connecting the upper portion of the vessel above the level of the liquid therein with the engine, the difference in level between the outlet of the goose neck and the bend of the steam pipe 80 being substantially equal to the height of a barometric column of the liquid.

In testimony whereof I have signed this 90 specification in the presence of two subscribing witnesses.
